CONTROL SYSTEM

Maurice E. Reagan and Willard A. Derr, Wilkinsburg, Pa., assignors to Westinghouse Electric Corporation, East Pittsburgh, Pa., a corporation of Pennsylvania

Application June 27, 1944, Serial No. 542,294

8 Claims. (Cl. 177—353)

Our invention relates, generally, to supervisory control systems, and it has reference, in particular, to control systems for controlling from a central control station, and providing indications of the operating position of, apparatus which is located remotely from a remote supervisory control station.

Generally stated, it is an object of our invention to provide a supervisory control system which is simple and inexpensive to manufacture, and which is flexible and positive in operation.

More specifically, it is an object of our invention to provide for remotely controlling and supervising the operation of apparatus which is positioned some distance from a remote supervisory control station over a single supervisory and control conductor between the apparatus and remote station.

Another object of our invention is to provide for extending a supervisory control system to include apparatus which is relatively distant from the remote station without requiring an excessive number of additional conductors or equipment.

It is also an object of our invention to provide for controlling an automatic reclosing circuit breaker at a location which is relatively distant from a remote supervisory control station and for indicating whether the circuit breaker is open and subject to reclosing, locked open, closed, or whether the control and supervisory channel between the circuit breaker and the remote supervisory control station is in operating condition.

Yet another object of our invention is to provide for utilizing a plurality of point supervision control relays in conjunction with a pair of supervisory control relays for effecting operation and supervision of a circuit breaker remotely located from a remote control station over a single conductor and at the same time maintain supervision of the conductor so as to obtain an indication when the conductor is shorted, grounded or open.

Still another object of our invention is to provide for maintaining supervision of the condition of a control and indication channel between an operating station and a circuit breaker remotely located therefrom, as well as effecting operating and obtaining an indication of the operating condition of the circuit breaker over a single control and indication conductor.

Other objects will, in part, be obvious and will in part, be explained hereinafter.

In practicing our invention in one embodiment thereof, control and supervision of a circuit breaker or other apparatus units located relatively distant from a remote supervisory control

station is effected over a single supervisory control conductor while maintaining supervision of the operating condition of the conductor. A pair of supervision control relays are used to provide a plurality of different stopping circuits for the counting chain at the remote station. Selective operation of the supervision control relays is effected by having a pair of point supervision relays connected to the source of control voltage in cascade with a supervisory control conductor extending intermediate the relays of the pair to the remote circuit breaker location. Auxiliary switch means are provided at the remote circuit breaker location for controlling the polarities applied to the control conductor in accordance with the position of the circuit breaker, thereby selectively controlling the positions of point supervision relays. Failure of the control conductor results in joint operation of the point supervision relays associated therewith, so as to provide for indicating a conductor fault. Control of the circuit breaker is effected over the same conductor, the circuit breaker control means being non-operative on the relatively small currents used by the supervision control relays.

For a more complete understanding of the nature and scope of our invention, reference may be made to the following detailed description in connection with the accompanying drawings which, when joined together with Figure 1 at the left and Figure 2 at the right, provide a diagrammatic view of a supervisory control system embodying the principal features of the invention, in which:

Figure 1 is a diagrammatic view of the central control station apparatus,

Fig. 2 is a diagrammatic view of the remote station apparatus together with the auxiliary equipment used at the remote circuit breaker location; and

Fig. 3 is a diagrammatic view of a control and indicating system embodying the invention in another of its forms.

The preferred embodiment of our invention is shown and described herein as applied to the supervisory control system disclosed in the Boswau Patent No. 2,091,301 issued August 31, 1937, and assigned to the assignee of the present invention. For the purpose of simplification, most of the elements of the system of the Boswau patent are shown herein in the same cooperative relation as in the Boswau patent and bearing the same reference characters as in the Boswau patent drawing. Certain relays, conductors and other elements of structure have been omitted, and others have been added, and certain relay

contact elements have been added to the relays of the Boswau patent in order to perform different functions. These elements have been designated by reference characters, not found in the Boswau patent. Since no changes were made in the control station coding, selecting, and control apparatus, shown in Fig. 2 of the Boswau patent, this portion of the system has been shown boxed in Fig. 1 with the same conductors connecting it to other portions of the system, as shown in the Boswau patent. Since only relatively minor changes were made in connection with the circuit breaker control relay 414 of Fig. 4 of the Boswau patent, the substation coding, selecting, and control apparatus of Fig. 4 thereof has been shown herein as boxed in Fig. 2 with the circuit breaker control relay 414, illustrated as boxed therein, in order to show the changed circuit connections.

While it is common to control remotely located circuit breakers from a control station by a supervisory control system such as that shown in the Boswau patent hereinbefore referred to, the circuit breakers, thus controlled, are usually located relatively close to the supervisory control apparatus at the remote station. Hence, it is usually no problem to provide the necessary control and supervisory circuit between the supervisory apparatus and the circuit breakers. However, in many instances the circuit breakers to be controlled by means of a supervisory control system are not all located close to a single location but are scattered over a relatively wide area. One example of this situation is in the case of the power supply to a subway system wherein the circuit breakers may be scattered along the length of the subway line. In such case it becomes necessary to select one or more remote control stations for the supervisory control system and then further provide for extending the supervisory control system from the remote stations to the individual circuit breaker locations.

Referring to Fig. 2 of the drawings, the reference numerals 500 and 502 may denote generally circuit breaker locations which may be relatively distant from the remote control station and the rest of the supervisory and control apparatus shown in the figure. The circuit breakers (not shown) at these locations may be of the automatic reclosing type and of the non-reclosing type respectively, in order to illustrate the different features of the invention.

In order to provide for extending the operation of the supervisory control equipment from the remote substation to the circuit breaker location at 502 where a non-reclosing circuit breaker may be located, a single supervisory and control conductor 503 may be provided in connection with the circuit breaker location 502 which may be designated as point 4 on the supervisory control system where it may be desired to control and supervise the operation of the circuit breaker associated with that point, and at the same time maintain supervision of the control conductor 503.

In order to provide for indicating not only when the circuit breaker is open or closed but also whether the supervisory control conductor 503 is free from faults, the supervision control relays 507 and 508 may be added to the system of the Boswau patent. These relays have a plurality of contact members cooperative to provide a plurality of different stopping circuits for the point selecting relays 303 through 308 of the counting chain at the remote station. Additional contact members may be added to the relays 305 and

307, in order to provide additional stopping points for the chain.

Control of the supervision control relays 507 and 508 may be effected by means of a pair of point supervision relays 509 and 510, which also control the operation of the point relay 313, and which may be connected in cascade across the common source of direct current control voltage so as to be normally operated to the energized position. A connection may be provided from therebetween to the supervisory control conductor 503 so that either one or the other of the point supervision relays may be shunted down and the other picked up, depending on the polarity of the control voltage applied to the supervisory control conductor 503.

The polarity of the supervisory control conductor 503 may be varied by connecting the circuit breaker end thereof to either negative or 20 positive polarity through either the tripping relay 319 or the closing relay 320 by means of an auxiliary circuit breaker switch 321'. For this reason the connections of the circuit breaker control relay 414 may be changed by adding an additional armature 531 for placing negative polarity 25 on the closing relay 320 to operate it.

In order to provide for effecting operation of the point supervision relays without at the same time operating either of the tripping or the closing 30 relays, the point supervision relays may be disposed to operate on relatively small control currents which are insufficient to operate the tripping or closing relays. The resistance of the point supervision relays may be sufficiently high, 35 so as to limit the control current therethrough to a value less than that required for operating either of the tripping or closing relays.

Where the circuit breaker at the remote location is provided with automatic reclosing means 40 so that the circuit breaker will reclose after tripping due to a fault, it will be necessary for the operator at the central control station to know not only whether the circuit breaker is open or closed, but whether it is open and subject to reclosing by the automatic reclosing means upon the removal of the fault or whether it is locked open. This indication is necessary so that the operator may know whether it is safe for a repairman to work on circuits controlled by a circuit breaker which is open.

In order to provide this additional indication and also maintain supervision of the control channel between the circuit breaker location and the remote substation, a pair of supervisory control conductors 512 and 513 may be provided between the circuit breaker location 500 and the remote station. At the remote station, two pairs of cascade connected point supervision relays 515, 516 and 517, 518 may be provided in connection 55 with the supervisory control conductors 512 and 513, respectively. Associated make-and-break contacts of these point supervision relays may be interposed in the energizing circuit of the point relay 311 to provide for deenergizing it upon a change in the operating condition of any one of the point supervision relays. Additional contact members may be provided on the point supervision relays for providing different control circuits for the supervision control relays 507 and 508 which determine the different stopping points 60 of the counting chain, comprising relays 303 through 308.

In order to provide for selectively operating the point supervision relays 515 through 518 in accordance with the condition of the circuit break-

er and the supervisory control conductors, an auxiliary switch 318' on the circuit breaker at the remote location 500 may be utilized for connecting either positive or negative polarity to the supervisory control conductor 513, depending on whether the circuit breaker is open or closed. The auxiliary switch 318' may also be used to connect one or another of the terminals of the closing relay 317 to the positive or negative terminal of the source.

For the purpose of supervising whether or not the circuit breaker is merely open and subject to reclosing upon the removal of a fault condition, or whether it is locked open, a circuit breaker control switch 520 may be used for controlling the connection of the supervisory control conductor 512 to either positive or negative polarity through the operating winding of the trip relay 316. The circuit breaker control switch may be of toggle or latch type having trip and close operating windings 522 and 523, respectively, for operating the armature 524 to either the trip or close position wherein it remains until operated to the other position.

The circuit breaker may be locked out by operating the circuit breaker control switch 520 to the trip position whereupon the reclosing circuit for the circuit breaker may be interrupted by the opening of contact members 520 at the same time a supervisory signal is sent to the control station in a manner which will be described hereinafter.

In order to provide for supervision of the additional functions at the central control station, the lamp relays 128 and 130 of the Boswau patent at points 1 and 4 may be replaced by associated pairs of lamp relays 128', 128'', and 130' and 130'', respectively. Additional contact members may be added to the point selecting relays 140, 141, 142 and 143 and an extra contact may be added to the signal relay 132 in order to provide for selectively controlling the operation of these point lamp relays to light both the red and green lamps when the supervisory control conductors between the circuit breakers and the remote stations are subject to a fault condition. In the case of the circuit breaker at location 500 which is designated as point 1 on the system, the point lamp relays also perform the additional function of lighting an amber lamp 526 when the circuit breaker is open but not locked open.

Referring to Figs. 1 and 2, it will be seen that the apparatus associated with the circuit breaker at the location 500 is shown for the closed position of the circuit breaker with the point supervision relays 515 and 517 up and the point supervision relays 516 and 518 down. The circuit breaker control switch 520 is in the close position. Accordingly, the point lamp relay 128' at the control station is up, providing an energizing circuit for the red lamp 109 which indicates that the circuit breaker is closed. Should the circuit breaker open due to a fault condition, the auxiliary switch 318' moves to the open position, connecting the supervisory control conductor 513 to the positive terminal through the operating winding of the closing relay 317. The point supervision relay 517 is thereby shunted down and the point supervision relay 518 picks up momentarily interrupting the holding circuit for the point supervisory relay 311, which drops and remains deenergized.

An energizing circuit is thereby provided for the substation starting relay (not shown) of the substation coding, selecting and control apparatus. The counting chain starts to pulse and

sends out two pulses or one control pulse to select point 1 at the central control station, relays 303, 302, 304, 301 picking up in sequence, and relays 303, 302 dropping out. At this point a stopping circuit for the chain is provided from the substation coding, selecting and control apparatus through conductor 527, armature 528 and back contact of the point supervisory relay 311, and front contact and armature 529 of the point selecting relay 304 to effect energization of the stopping relay of the substation control apparatus.

At the central control station, the point selecting relays 138, 137, 139 and 136 pick up and relays 138, 137 drop out in synchronism with the relays 303, 302, 304 and 301 of the remote station. An energizing circuit for the alarm 105 is provided by the alarm relay 127 which picks up and the point selecting relay 138 picks up and rings until the release key 103 is depressed. When relay 136 picks up, an energizing circuit is thereby provided for the point relay 133 at point 1 from negative through the operating winding of relay 133, front contact and armature 530 of point selecting relay 139, conductor 531 through front contact and armature 165 of sequence relay 136, back contact and armature 166 of sequence relay 135, back contact and armature 167 of sequence relay 134, to positive in the control station coding, selecting and control apparatus. Point relay 133 picks up and establishes an energizing circuit for the check lamp 107 through armature 532.

After a short delay when the receiving control relay of the coding, selecting and control apparatus of the control station drops, an energizing circuit is established for starting the control station counting chain to pulse and check the point selection operation. Relays 138, 137, 139 and 136 pick up in sequence, relays 138, 137 dropping out as soon as the relay 136 picks up. At this point a stopping circuit is established through front contact members and armature 530 of point selection relay 139 and front contact members and armature 533 of the point relay 133 to stop the chain from further pulsing.

At the remote station, relays 303, 302, 304 and 301 pick up in sequence, relays 303 and 302 dropping out when relay 301 picks up. An energizing circuit is thus established for the point relay 309, extending from the negative terminal through the operating winding of relay 309, front contact and armature 534 of point selection relay 304, front contacts and armature 334 of sequence relay 301, back contact and armature 335 of sequence relay 300, back contact and armature 336 of sequence relay 302 to the positive terminal in the remote station coding, selecting and control apparatus.

Point relay 309 in picking up sets up a circuit which starts the remote station counting chain pulsing to supervise an indication of the changed position of the circuit breaker. Due to point supervision relay 517 dropping and point supervision relay 518 picking up, the energizing circuit for the supervision control relay 507 is interrupted by armature 535, and the relay 507 drops. A circuit is thus established from positive through armature 536 and front contact of the point relay 309, back contact and armature 537 of the point supervisory relay 311, armature 538 and back contact of supervisory control relay 507, armature 539 and front contact of supervisory control relay 508, front contact and armature 540 of point selecting relay 305, for stopping the

counting chain at the remote station from pulsing after two control pulses to signal that the circuit breaker is open but not locked out.

At the same time negative polarity is placed on the point supervisory relay 311 through front contact and armature 352 of relay 351', conductor 541, armature 543 and front contact of the point relay 309, and the armatures and contacts of the point supervision relays 515, 516, 517 and 518. At the central control station, the counting chain pulses in synchronism with the remote station chain, and at the second control pulse, an energizing circuit is established for the lamp control relay 132 which picks up. This puts positive voltage on the point lamp relay 128', through armature 542 and front contact of point selecting relay 140, armature 543 and front contact of the lamp control relay 132, and armature 544 and front contact of the point relay 133, dropping it and extinguishing the red lamp. At the same time positive voltage is put on the point lamp relay 128'' through armature 545 and front contacts of the point selecting relay 140, armature 171 and front contact of the lamp control relay 132, armature 546 and front contacts of the point relay 133, dropping the point lamp relay 128'' and completing an energizing circuit for the amber lamp 526 which indicates that the circuit breaker is open but not locked out. The green lamp 113 is extinguished due to its energizing circuit being opened when the point lamp relay 128'' drops. After a predetermined time delay, the supervisory control system automatically restores itself to the deenergized or normal condition.

In order for the operator to lock the circuit breaker at location 500 open and make it safe for a repairman to work on the circuits controlled thereby, the operator must go through a manual tripping operation, first turning the twist key 110 to trip position so that springs 111 and 112 engage their outer contacts, and depressing the point key 114 which shunts the individual point relay 129 through spring 115 and establishes an energizing circuit through spring 116 for starting the central control station counting chain to pulse. Relays 138, 137, 139 and 136 pick up in sequence, relays 138 and 137 dropping out when relay 136 picks up, to send out a selection code of one control impulse. An energizing circuit is thereby provided for stopping the selection code through armature 547 and front contact members of the point relay 129, and front contact members and armature 548 of the point selection relay 139.

At the remote station, the point selection relays 303, 302, 304 and 301 pick up and relays 303, 302 drop out in synchronism with the relays 138, 137, 139 and 136 of the control station, providing an energizing circuit for the point 1 point relay 309 associated with the circuit breaker at location 500. After a predetermined time delay, the relays 303, 302, 304 and 301 again pulse to send a check code of one control impulse and check the selection of the point relay 309. At the control station the relays 138, 137, 139 and 136 pulse and the point relay 133 picks up, lighting the check lamp 107 when the check code is received.

The operator then depresses the master control key 102 closing contact 101, which starts the counting chain pulsing to send out three operation control pulses for operating the circuit breaker control switch to the trip position. The counting chain of the control station stops at three control impulses when point selection relay

141 and sequence relay 135 pick up to provide a stopping circuit from positive through armature 546 and front contact of the point relay 133, armature 550 and back contact of the point supervisory relay 129, contact spring 112 and outer contact member of the control key 110, conductor 179 and conductor 551 through front contact and armature 198a of the point selection relay 141.

10 At the remote station, counting chain relays 303, 302 through 306, 336, 334 and 335 pulse in synchronism with the relays of the control station providing an energizing circuit for the circuit breaker control relay 414 which picks up. Energization of the circuit breaker control relay 414 puts a positive potential on the trip relay 316 from positive through armature 450 and front contact of relay 414, conductor 553, armature 353 and front contacts of point selection relay 306, conductor 554, armature 555 and front contacts of the point relay 309, supervisory control conductor 512, operating winding of trip relay 316, contact members 526b to negative. Trip relay 316 picks up and establishes an obvious energizing circuit for the trip winding 522 of the circuit breaker control switch 520, which operates to the trip position and opens contact members 520a to interrupt the reclosing circuit of the circuit breaker and lock the circuit breaker out.

15 A positive voltage is thereby placed on the supervisory control conductor 512 through contact members 520c, dropping point supervision relay 515 and picking up point supervision relay 517, so that supervision control relay 507 is now up, and supervision control relay 508 is down. The changed position of the point supervision relays 515 and 516 interrupts momentarily the energizing circuit for the individual point relay 311 so that it drops and starts the remote station counting chain pulsing to send a supervision code. The chain pulses until positive voltage is put on the stopping relay through the front contacts of supervision control relay 507, back contacts of supervision control relay 508 and front contacts and armature 354 of point selection relay 306. Three control impulses are thus sent to indicate that the circuit breaker is open and locked out.

20 At the control station, the relays 138, 137, 139 and 136 through 141 pick up and drop out in synchronism with the relays of the remote station counting chain, providing an energizing circuit for the signal control relay 132. The relay 132 in turn places positive and negative on the point lamp relays 128' and 128'' respectively, through armatures 543 and 171 of the relay 132 and armatures 180 and 557 of point selection relay 141 respectively. The point supervision relay 129 is also picked up by negative polarity being applied through armature 174 of relay 132 and armature 558 and front contact of the point relay 133.

25 The point lamp relay 128' stays down and the point lamp relay 128'' picks up. The circuit for the amber lamp 526 is interrupted by armature 550 which engages its front contact and places positive polarity on the green lamp, indicating that the breaker is open and locked out so that it is safe to work on the circuits associated therewith.

30 Closure of the circuit breaker may be effected over the supervisory control system in the usual manner, first depressing the point key 110 to select point 1, then operating the twist key 110 to the close position and depressing the master key 102. The circuit breaker control relay 414 is op-

erated in response to the close code of five control impulses and negative polarity is applied to the operating winding of the closing relay 317 over the supervisory control conductor 513. The circuit breaker control switch 520 is thereupon actuated to the close position and the circuit breaker is closed. The usual supervisory signals are sent and the indications of a closed breaker appear at the central control station.

Should either or both of the supervisory control conductors 512 or 513 have a fault thereon, being open, grounded or shorted, the control voltage will be removed from either or both of the point supervision relays 515, 516 or 517, 518. Both of the relays of the pair from which the voltage is removed will operate to the energized position. Accordingly, the individual point relay 311 is dropped to start the remote station counting chain pulsing to select the proper point at the control station. Subsequently, due to the fact that both of the supervision control relays 507 and 508 will be deenergized, a supervisory signal of four control impulses will be sent to indicate an open wire or a fault thereon.

At the control station, the alarm relay 127 operates and both the point relay 133 and the signal control relay 132 will energize in order, so that energizing circuits will be established for both of the point lamp relays 128' and 128'' through front contact members and armatures 543 and 171 of the signal control relay, and front contacts and armatures 562 and 563, respectively, of the point selection relay 142. Accordingly, both the red and green lamps will be lighted, indicating an open supervisory control line condition. The disagreement lamp 108 will also be lighted, regardless of whether the control key 110 is in the close or trip position, through the armature and front contact of either point lamp relay 128'' or 128'.

In connection with the circuit breaker location 502, which may, for example be denoted as point 4 on the supervisory system, it will be observed that the single pair of point supervision control relays 509 and 510 are selectively operable depending on the polarity applied to the control conductor 503 or the absence thereof, to energize either the supervision control relay 507, or both of the supervision control relays 507 and 508, or to deenergize both of them, in order to provide three different stopping circuits for the remote station counting chain. Since the circuit breaker at location 502 is not arranged for automatic reclosing, these operating positions of the supervision control relays may be used to indicate that the circuit breaker is tripped, that it is closed, or that there is a faulty supervisory control conductor condition. The circuit breaker trip and closing relays are likewise operated over the supervisory control conductor under the control of the control relay 414 and the auxiliary circuit breaker relay 321'.

At the control station, the point lamp relays 130' and 130'' associated with point 4 operate in substantially the same manner as the point lamp relays 128' and 128'' of point 1 to control the operation of the associated indicating lamps, except that an amber lamp is not provided, and the red and green lamps are used in the usual manner to merely indicate whether the circuit breaker is closed or open. Since this type of supervisory control circuit is used on circuit breakers not having automatic reclosing, the additional indication of whether the circuit breaker is locked out is not necessary since there is no danger of the

circuit breaker reclosing due to the removal of a fault condition while the repairman is working on the circuits.

Supervision of the single supervisory and control conductor is provided in the same manner as set forth in the description in connection with the circuit breaker at location 500. When the control voltage is removed from the conductor 503, both of the point supervision relays 509 and 510 operate. Both of the supervisory control relays 507 and 508 are thereby deenergized, and a code of four control impulses is sent to indicate a fault condition on the conductor.

It will be apparent from the above description and from Fig. 3 of the drawings that the extended portion of the supervisory control scheme may in itself comprise a useful subcombination where it is desired to operate and effect an operating condition of remotely located apparatus without using the supervisory and control equipment of the Boswau patent. In such instance the control conductor 503 may be used in conjunction with a manual control switch 565 which may be operated to apply either a negative or a positive control voltage to the single supervisory and control conductor 503 for selectively energizing the trip or close relays 319 or 320 at a remote circuit breaker location.

Supervision may be effected by means of green and red signal lamps 567 and 568 which may be connected to the common source in cascade and provided with an intermediate connection to the supervision and control conductor 503, or they may be controlled by the point supervision relays 509 and 510 similarly connected.

Accordingly, with the circuit breaker open and positive potential applied to the supervisory control conductor 503, point supervision relay will be up and the green lamp 568 will be lighted. The breaker may be closed by moving the switch 565 to apply negative potential to the conductor 503, thus energizing the close relay 320. The auxiliary circuit breaker switch operates and applies negative polarity to the conductor 503 so that the point supervision relay 510 drops to extinguish the green lamp 568 and the point supervision relay 509 picks up lighting the red lamp 567 to indicate that the circuit breaker is closed. A fault on the conductor 503 removes the control potential so that both point supervision relays pick up, and the red and green lamps light to indicate a conductor fault.

From the above description and accompanying drawings, it will be apparent that we have provided a new and novel manner for supervising and controlling circuit breakers or other apparatus units which are located remotely from a remote supervisory station, and at the same time providing for supervision of the supervisory control conductors extending between the remote station and the circuit breaker location. This extension of the supervisory control system provides positive supervision and control of the remotely located circuit breaker and may be used apart from the supervisory control system for effecting operation of apparatus at remote locations and obtaining an indication thereof without the necessity of the usual supervisory coding equipment.

Since certain changes may be made in the above described construction, and different embodiments of the invention may be made without departing from the spirit and scope thereof, it is intended that all matter contained in the above description or shown in the accompanying draw-

ings should be considered as illustrative and not in a limiting sense.

We claim as our invention:

1. In a supervisory control system having a plurality of control points at a remote station associated with apparatus located remotely therefrom and selectively controllable from a central control station over a supervisory control channel, a chain of counting relays at each station cooperative to select a point to be controlled or indicate an operation of the apparatus associated with said point and check said operation, a single control and supervision conductor extending from the remote station to the apparatus location, means at the apparatus location normally effective to maintain one polarity or the other on the conductor depending on the condition of the apparatus, means at the remote station selectively responsive to either polarity or the absence thereof on said conductor to provide different stopping circuits for the remote station counting chain at different points in the operating sequence, and means at the control station controlled by the counting chain thereat for indicating the condition of the apparatus and of the supervisory and control conductor.

2. A supervisory control system for an apparatus unit distantly positioned from a remote station comprising, supervisory and control apparatus including a chain of counting relays located at each of a control station and the remote station operable in synchronism in response to changed conditions at either station, a single supervisory and control conductor extending from the apparatus unit position to the remote station, auxiliary switch means responsive to the apparatus unit position for normally maintaining either positive or negative polarity on said conductor depending on the position of the apparatus unit, and control means at the remote station normally responsive to the polarity of the conductor to provide different stopping circuits for the remote station counting chain to effect an indication of the apparatus unit position and further responsive to the absence of either polarity on the conductor to provide a still different stopping circuit for the remote station counting chain to effect an indication of a faulty supervisory and control channel.

3. A supervisory control system comprising, supervisory control means including a chain of relays at each of a remote and a control station operable in synchronism over a single supervisory control channel in response to an initiating signal from either station, supervision control means operable to provide different stopping circuits for the chain of relays at the remote station, a pair of point supervision relays controlling the operation of the supervision control means, a single supervision and control channel connecting the point supervision relays to a circuit breaker location removed from the remote station, circuit means at the remote station providing operating circuits for the point supervision relay means to effect operation of the supervision control means to provide indication of a faulty supervision and control channel, and means normally responsive to the position of the circuit breaker to apply either a positive or a negative control potential to the supervision and control channel to render one or another of the point supervision relays inoperative and effect an indication of the circuit breaker position.

4. The combination in a supervisory control system having supervisory control apparatus at remote and control stations including a chain of

counting relays at each station operable in synchronism to transmit or receive coded series of impulses, of supervisory control means at the remote station operable to stop the remote station counting chain at a plurality of different points, a pair of point supervision relays providing a plurality of circuits for the supervisory control means, said relays being normally connected in cascade to a source of control voltage for providing operation of the supervision control means to effect a predetermined supervisory code signal, and a single supervisory control conductor associated with a circuit breaker and the point supervision relays for jointly applying either a positive or a negative control voltage to the point supervision relays in accordance with the position of the circuit breaker to shunt one or another of them and operate the supervisory control means to effect one or another of different predetermined supervisory code signals to indicate the circuit breaker position.

5. In a supervisory control system having supervisory control apparatus at remote and control stations each with a chain of counting relays operable from either station in synchronism to control and indicate the position of an apparatus unit located distantly from the remote station, a pair of supervision control relays selectively operable to provide a plurality of stopping points for the remote station counting chain, a single supervisory and control conductor extending from the remote station to the apparatus unit location, means at the apparatus unit location for applying control potentials of opposite polarities to the conductor depending on the position of the apparatus unit, and a pair of point supervision relays operable in response to the polarity of the control conductor to effect operation of the supervision control relays to indicate the apparatus unit position, said relays being connected in cascade to a source of control voltage for effecting operation of the supervision control relays to indicate a conductor fault when the control voltage on the control conductor is rendered ineffective at the remote station.

6. A supervisory control system comprising, supervisory and control equipment located at remote and control stations including a chain of counting relays at each station operable in synchronism from either station, a circuit breaker located remotely from the remote station, a single supervisory and control conductor extending from the remote station to the circuit breaker, means at the circuit breaker location operable to apply control voltages of opposite polarities from a source to the control conductor depending on whether the circuit breaker is open or closed, a pair of point supervision relays connected to the source of control voltage and to the control conductor so as to be jointly operable when the control voltage on the control conductor is reduced below a predetermined value and selectively operable depending on the polarity of the control voltage on the control conductor when it is above the predetermined value, a plurality of supervision control relays operable under the control of the point supervision relays for controlling the remote station counting chain to produce different code signals depending on the positions of the point supervision relays, and indicating means at the control station operable under the control of the control station counting chain to indicate whether the circuit breaker is open or closed or whether there is a fault on the control conductor.

7. A supervisory control system comprising, supervisory control equipment located at remote and control stations including a chain of counting relays at each station operable in synchronism from either station, a plurality of supervision control relays at the remote station operable to provide a plurality of stopping circuits for the counting relays at the remote station for indicating different conditions of the system, a circuit breaker having means for automatically reclosing after tripping due to a fault and located remote from the remote station, supervisory tripping and closing means of the control system associated with a circuit breaker located remote from the remote station and having means for effecting automatic reclosing after tripping, switch means associated with the circuit breaker for connecting one terminal of the closing means to one terminal of a direct current source when the circuit breaker is closed and the other terminal of the closing means to the other terminal of the source when the circuit breaker is open, control switch means operable under the control of the supervisory tripping and closing means to control the tripping and closing circuits of the circuit breaker and connect one terminal of the supervisory tripping means to one or the other terminals of the source depending on whether the control switch is in the trip or the close position, a supervisory control conductor extending from the other terminal of each of the supervisory tripping and closing means to the remote control station, and a pair of point supervision relays for each conductor said relays being connected in cascade across the source and having

connections intermediate the relays of one pair to one control conductor and intermediate the relays of the other pair to the other conductor.

8. A supervisory control system comprising, 5 supervisory control apparatus located at remote and control stations and connected by a supervisory control channel, said apparatus including a chain of counting relays at each station operable in synchronism from either station, supervisory tripping and closing means operable over the supervisory channel for a circuit breaker distantly located from the remote station means operable to automatically reclose the circuit breaker subsequent to a fault condition, control 10 means operable in response to operation of the supervisory tripping means to prevent reclosing thereof by the automatic reclosing means, a supervisory control conductor extending from each of the supervisory tripping and closing means, 15 means associated with the control means and the circuit breaker for connecting the conductors to one or the other terminals of a direct current source depending on whether the control means and the circuit breaker are in the trip or closed position, and a pair of control relays associated 20 with each control conductor cooperative to provide different stopping circuits for the remote station counting chain to produce different supervisory code signals for effecting indications 25 at the control station depending on whether the circuit breaker is merely open, locked open or closed, and whether the control conductors have 30 a fault condition thereon.
